UNITED STATES PATENT OFFICE.

EDWARD KIRBY BOTTLE, OF ELMIRA, NEW YORK, ASSIGNOR TO AMERICAN SALES BOOK COMPANY, LIMITED, OF TORONTO, ONTARIO, CANADA, A CORPORATION OF ONTARIO, CANADA.

MANIFOLDING DEVICE.

1,174,047.

Specification of Letters Patent. Patented Mar. 7, 1916.

Application filed April 25, 1912. Serial No. 693,025.

To all whom it may concern:

Be it known that I, EDWARD KIRBY BOTTLE, a citizen of the United States, residing at Elmira, in the county of Chemung 5 and State of New York, have invented certain new and useful Improvements in Manifolding Devices, of which the following is a full, clear, and exact description, such as will enable others skilled in the art 10 to which it appertains to make and use the same.

This invention relates to manifolding devices, and with regard to certain more specific features thereof, to receptacles, each 15 upper surface of which forms a writing table across which a plurality of record sheets with manifolding media are adapted to be drawn.

One of the objects of the present invention is to provide a simple and practical device of the above character which will be cheap to manufacture.

Another object is to provide a compact and self-contained device into which the 25 record sheets may be easily and quickly inserted without manipulation of any special mechanism.

A further object is to provide a device of the above character which will be durable 30 in construction and efficient in use.

Other objects will be in part obvious and in part pointed out hereinafter.

The invention accordingly consists in the features of construction, combinations of 35 elements and arrangement of parts which will be exemplified in the construction hereinafter set forth, and the scope of the application of which will be indicated in the following claims.

40 In the accompanying drawings, wherein are shown two of various possible embodiments of this invention,—Figure 1 is a central longitudinal section of one form of the complete device; Fig. 2 is a plan view thereof; Figs. 3 and 4 are detail views of certain parts of the device shown in Figs. 1 and 2; Figs. 5 and 6 are a longitudinal section and plan view, respectively, of a modification of the present invention; and Fig. 7 is a perspective view of a portion of the web.

50 Similar reference characters refer to similar parts throughout the different views of the drawings.

Referring now to Figs. 1 and 2 in par-

ticular, there is denoted at 1 a rectangular 55 receptacle, the upper part of which is provided with a cover 2 hinged along one side at 3 and provided with suitable fastening means at its opposite side, whereby the receptacle may be easily and quickly opened 60 to replace the record sheet. Near one end of the receptacle, and preferably between the upper and lower parts thereof, is provided an opening 4 through which the web may be drawn prior to passing over the 65 upper surface of the receptacle which is used as a writing table.

The record sheet preferably employed in the present embodiment comprises a single web folded back and forth upon itself in 70 a longitudinal direction, as shown in Fig. 7, forming longitudinal folding lines 5, 6 and 7. The web is also folded transversely to itself along the lines 8 (Fig. 1), and then the entire pad or web is folded again at 9 75 into the compact arrangement, as clearly shown. The web is drawn from the interior of the folded pad through the opening 4, a transverse guide 8' mounted upon the upper edge of the receptacle and between vertically disposed guides 9' and 10. Positioned 80 between these guides and at each side of the receptacle are a plurality of rotary cutters 11, 12, 13 and 14, respectively. Each of these cutters is mounted on a separate 85 bracket 15, which in turn is pivotally mounted at 16 to the side of the receptacle, whereby it may be swung out of the path 90 of travel of the web, as shown by the position of the cutter 14.

While the present device is herein shown and described with relation to its application of a quadruplicate device, it is, of course, to be understood that by swinging the cutters into and out of operative relation, a web from which any desired number of records of a transaction may be obtained, according to the number of folds in the web, may be handled.

From the above it will be clear that as 100 the web is drawn longitudinally over the upper surface of the receptacle these cutter blades, which are inserted between the adjacent pairs of leaves into which the web is to be subsequently divided, stretch the paper 105 laterally to remove wrinkles, define the fold and cut the web along its longitudinally folded lines. For instance, the cutter 11

will cut along the fold 5, the cutter 12 along the fold 6, while the cutter 13, at the opposite side, will cut along the fold 7 at the opposite side of the web. If a web to be divided into five leaves were used, the cutter 14 would be swung over into operative position to coact with the added fold.

After the web is severed into leaves, it is drawn past the opposite end of the receptacle which forms the writing table proper and through a holding clip 17, which also provides a cutting edge along which the leaves may be severed after being drawn out away from the writing table, as shown by the free ends in Fig. 1.

The manifolding medium in the present embodiment comprises a plurality of carbon sheets 18, in this case three, wound upon a single roll 19 positioned in a receptacle 20 along one of the longitudinal sides of the receptacle. The carbon sheets are drawn out through an opening 21, shown in Fig. 4, and across the table transversely to the movement of the record leaves. Each carbon sheet, of course, passes between an adjacent pair of record leaves. The free ends of the carbon sheets are secured by a holder or clip 22 along the opposite longitudinal edge of the receptacle, which also acts as a cutting edge for tearing off the worn carbon sheets.

In order to prevent the carbon sheets from being torn or mutilated by the rough cut edges of the record leaves as they are drawn along the table, there is provided a plurality of carbon clips 23, as shown in detail view in Fig. 3. These carbon clips are pivoted at 24 beneath the hinged cover of the carbon roll receptacle, and are provided at their free ends with a turned over portion 25 in line with the edges of the web. This alignment is maintained by vertically disposed guides 26 and 27. Adjacent the pivot 24 is a projecting shoulder 28 which engages a pin 29 to hold the same in proper position. If only two carbon sheets are used, one of these clips is swung out of the path of travel of the record sheets, as shown in dotted position 30. These clips, as shown in Fig. 2, are disposed at opposite sides of the paper table, where the greatest tendency to tear the carbon sheets occur.

A convenient method of operating a device of this character substantially as follows: Assuming the folding web to be positioned within the receptacle, as shown in Fig. 1, the end thereof is drawn out through the opening 4 and passed through the guide 8', with the cutters arranged as above described, each engaging one of the longitudinal folds. As the paper is drawn along the table the rotary cutters will sever the web into individual leaves. The upper leaves are then turned back and the lower

55 carbon sheet drawn out from the roll

through the opening 21 and laid thereover, its upper edge being engaged by the clips 23. The second record sheet is laid thereover and the next carbon sheet placed in operative relation thereto, and so on until 70 all of the leaves and carbon sheets are positioned in this alternate order. The free edges of the carbon sheet are caught and held by the clip 22 at the opposite side of the table, and the free edges of the record 75 leaves similarly engaged by the holder or clip 17. The device is then ready for use. The transaction is recorded upon the upper leaf and reproduced through the carbon sheets upon the lower leaves. After completing the transaction the record leaves are drawn out and the upper three torn along the upper edge or clip 17, while the lower leaf passes through an opening 31 in the end of the receptacle and is wound on 80 a roller 32, which may be manipulated by means of a knob 33 projecting to one side. A permanent record of all the transactions of the machine is thus obtained.

It is of course to be understood that the 90 term "cutter" or "cutting edge" used in referring to the rotary cutters and edge 17 is to be interpreted as a means for either cutting or exerting a tearing action on the web as it is manipulated.

Referring now to the modification shown in Figs. 5 and 6, the general construction and operation are substantially the same. Instead of providing rotary cutters as shown in Figs. 1 and 2, there is provided 100 a plate 34 hinged at each side of the receptacle in the same relative position as the cutter rolls. Diagonal cutter blades 35 may be inserted between the folds of the web and cut it along its folded lines in the manner above described. Owing to the diagonally disposed position of these blades, there will be exerted upon the web a lateral movement toward the fixed guides 9' and 10, thus preventing any intermediate bulging or irregularity as the leaves are subsequently fed along the writing table. Instead of providing a plurality of separate clips at each side of the receptacle for the carbon sheets, there is provided a single 110 V-shaped clip 36 hinged at one side 37 for each carbon sheet and extending entirely across the table to protect the edge. It will also be noted that in this modification, the transverse fold 9 in the web is omitted, so 115 that the receptacle holding the same number of leaves will be of less height and of greater length, the difference being clearly apparent from Figs. 1 and 5.

As the method of operation of this modification is substantially the same as that above described in connection with Figs. 1 and 2, it is thought to be unnecessary to repeat the same here.

As many changes could be made in the 130

above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In a manifolding device and in combination, a receptacle having an opening in one end, a longitudinally folded web passing through the opening, a writing surface, a plurality of cutters for cutting the web along its folded lines into a plurality of separate strips, a plurality of carbon sheets between the adjacent pairs of strips, and a transverse cutting edge along which the strips may be severed.

2. In a manifolding device, in combination, a receptacle having an opening near one end thereof through which a longitudinally folded web may be drawn, a cover for said receptacle, a plurality of movable cutters for severing the web along its folded lines into separate strips as the web is drawn across the upper surface of the receptacle, and a plurality of carbon sheets mounted upon said receptacle so as to be drawn in a direction transverse to the movement of the web and to be interposed between the adjacent pairs of strips for producing multiple copies.

3. In a manifolding device, in combination, a covered receptacle having an opening near one end thereof through which a longitudinally folded web may be drawn, a plurality of movable cutters for severing the web along its folded lines into separate strips as the web is drawn across the upper surface of the receptacle, a plurality of carbon sheets mounted upon said receptacle so as to be drawn in a direction transverse to the movement of the web and to be interposed between the adjacent pairs of strips for producing multiple copies, and a cutting edge along which the strips may be severed after being written upon.

4. In a manifolding device, in combination, a covered receptacle having an opening near one end thereof through which a longitudinally folded web may be drawn, a plurality of movable cutters for severing the web along its folded lines into separate strips as the web is drawn across the upper surface of the receptacle, a plurality of carbon sheets mounted upon said receptacle so as to be drawn in a direction transverse to the movement of the web and to be interposed between the adjacent pairs of strips for producing multiple copies and a cutting edge along which the carbon sheets may be

severed after being drawn from between the strips of the web.

5. In a manifolding device, in combination, a covered receptacle having an opening near one end thereof through which a longitudinally folded web may be drawn, a plurality of movable cutters for severing the web along its folded lines into separate strips as the web is drawn across the upper surface of the receptacle, a plurality of carbon sheets mounted upon said receptacle so as to be drawn in a direction transverse to the movement of the web and to be interposed between the adjacent pairs of strips for producing multiple copies, a cutting edge along which the strips may be severed after being written upon, and a cutting edge along which the carbon sheets may be severed after being drawn from between the strips of the web.

6. In a manifolding device, in combination, a covered receptacle having an opening near one end thereof, a longitudinally and transversely folded web positioned within said receptacle so as to be drawn through said opening and over the upper surface of the receptacle, means for severing the web along its longitudinally folded lines into a plurality of strips, carbon sheets interposed between each adjacent pair of strips, and a plurality of movable means protecting the longitudinal edges of said carbon sheets.

7. In a manifolding device, in combination, a covered receptacle, a longitudinally and transversely folded web positioned within said receptacle so as to be drawn over the upper surface of the receptacle, means for severing the web along its longitudinally folded lines into a plurality of strips, carbon sheets interposed between each adjacent pair of strips, and a plurality of pivotally mounted clips engaging the longitudinal edges of said carbon sheets to prevent them from being torn by the rough edges of the several strips.

8. In a manifolding device, in combination, a covered receptacle having an opening near one end thereof, a longitudinally and transversely folded web within said receptacle so as to be withdrawn from said receptacle through said opening and thence over the upper surface of the receptacle, a plurality of cutters for severing the web along its longitudinally folded lines, into strips, a roll comprising a plurality of separate carbon sheets mounted at one side of said receptacle and so that when unwound from said roll the sheets lie across the path of travel of said web, a clamp for the free edges of the carbon sheets, and means for protecting the longitudinal edges of said carbon sheets to prevent them from being torn by the movement of the severed strips.

9. In a manifolding device, in combina-

tion, a covered receptacle, a longitudinally and transversely folded web within said receptacle adapted to be withdrawn from said receptacle and thence over the upper surface thereof, a plurality of cutters for severing the web along its longitudinally folded lines into strips, a roll comprising a plurality of separate carbon sheets mounted at one side of said receptacle so that when unwound from said roll the sheets lie across the path of travel of said web, a clamp for the free edges of the carbon sheets, means for protecting the longitudinal edges of said carbon sheets to prevent them from being torn by the movement of the severed strips, and means for holding the free edges of said strips.

10. In a manifolding device, in combination, a covered receptacle, a longitudinally and transversely folded web within said receptacle adapted to be withdrawn from said receptacle and thence over the upper surface thereof, a plurality of cutters for severing the web along its longitudinally folded lines into strips, a roll comprising a plurality of separate carbon sheets mounted at one side of said receptacle and so that when unwound from said roll the sheets lie across the path of travel of said web, a clamp for the free edges of the carbon sheets, means for protecting the longitudinal edges of said carbon sheets to prevent them from being torn by the movement of the severed strips, means for holding the free end edges of said strips, and a roller connected with said device upon which the lower strip may be wound to form a permanent record of all the transactions of the machine.

11. In a manifolding device, in combination, a covered receptacle having an opening near one end thereof, a longitudinally and transversely folded web within said receptacle adapted to be withdrawn from said receptacle and thence over the upper surface thereof, a plurality of cutters for severing the web along its longitudinally folded lines into strips, a roll comprising a plurality of carbon sheets mounted at one side of said receptacle so that when unwound from said roll the sheets lie across the path of travel of said web, a clamp for the free end edges of the carbon sheets, means for protecting the longitudinal edges of said carbon sheets to prevent them from being torn by the movement of the severed strips, means for holding the free edges of said leaves, and a roller upon which the lower strip may be wound to form a permanent record of all the transactions.

12. In a manifolding device, in combination, a covered receptacle containing a longitudinally folded web, and a pivotally mount-

ed cutter upon the upper surface of said receptacle adapted to cut the web along its longitudinal fold.

13. In a manifolding device, in combination, a receptacle containing a web folded back and forth upon itself in the direction of its length, and a pivotally mounted cutter at each side of said receptacle adapted to cut the web along its folded line into a plurality of separate strips.

14. In a manifolding device, in combination, a covered receptacle the upper surface of which forms a writing table across which a plurality of strips may be drawn, a carbon sheet between said strips, and means for protecting the longitudinal edge of said carbon sheet from being torn as the strips are moved transversely thereto.

15. In a manifolding device, in combination, a covered receptacle the upper surface of which forms a writing tabel across which a plurality of strips may be drawn, a carbon sheet between said strips, means for protecting the longitudinal edge of said carbon sheet from being torn as the strips are moved transversely thereto, and means for holding the free end edge of said carbon sheet.

16. In a manifolding device, in combination, a covered receptacle the upper surface of which forms a writing table across which a plurality of strips may be drawn, a carbon sheet between said strips, means for protecting the longitudinal edge of said carbon sheet from being torn as the strips are moved transversely thereto, means for holding the free end edge of said carbon sheet, and means associated with said device upon which the lower record strip may be wound to form a permanent record of all the transactions of the machine.

17. In a manifolding device, in combination, a covered receptacle containing a longitudinally folded web, and a rotary cutter mounted upon the upper surface of said receptacle across which the web is drawn to cut the web along its folded line.

18. In a manifolding device, in combination, a receptacle, the upper part of which forms a writing surface, said receptacle containing a writing tablet, said receptacle and over the writing tablet, said web being folded back and forth upon itself to form a pad and said pad being folded bodily once over upon itself.

In testimony whereof I affix my signature, in the presence of two witnesses.

EDWARD KIRBY BOTTLE.

Corrections in Letters Patent No. 1,174,047.

It is hereby certified that in Letters Patent No. 1,174,047, granted March 7, 1916, upon the application of Edward Kirby Bottle, of Elmira, New York, for an improvement in "Manifolding Devices," errors appear in the printed specification requiring correction as follows: Page 1, line 108, the imperfect word should read *cutter*; page, 4, strike out line 113 and insert the syllables and words *taining a web which is withdrawn from said*; and that the said Letters Patent should be read with these corrections therein that the same may conform to the record of the case in the Patent Office.

Signed and sealed this 11th day of April, A. D., 1916.

[SEAL.]

R. F. WHITEHEAD,

Acting Commissioner of Patents.

Cl. 11—36.
